Patented Oct. 4, 1966

205,907

METAL WORKING MACHINE HEAD

Charles A. Larsen, Union Grove, Wis., assignor to George Gorton Machine Company, Racine, Wis., a corporation of Wisconsin

Filed Nov. 10, 1965, Ser. No. 38,061

Term of patent 14 years

(Cl. D54—14)

Fig. 1

Fig. 2

Fig. 3

Fig. 5

Fig. 4

Fig. 6

FIGURE 1 is a perspective view of a metal working machine head embodying the new design, the view being taken generally from the front, right side thereof;

FIGURE 2 is another perspective view of the head of FIGURE 1, but taken generally from the left, front side thereof;

FIGURE 3 is a right side elevational view of the head;

FIGURE 4 is a front, elevational view of the head;

FIGURE 5 is a plan view of the head; and

FIGURE 6 is a rear elevational view of the head.

The broken lines in the several views are disclosed for illustrative purposes only.

I claim:

The ornamental design for a metal working machine head, substantially as shown and described.
